UNITED STATES PATENT OFFICE.

CHARLES C. SPREEN, OF DETROIT, MICHIGAN, ASSIGNOR TO KELVINATOR CORPORATION, OF DETROIT, MICHIGAN, A CORPORATION OF DELAWARE.

REFRIGERATING UNIT.

Application filed July 30, 1923. Serial No. 654,517.

To all whom it may concern:

Be it known that I, CHARLES C. SPREEN, a citizen of the United States, residing at Detroit, in the county of Wayne and State 5 of Michigan, have invented a certain new and useful Improvement in Refrigerating Units, of which the following is a full, clear, and exact description, reference being had to the accompanying drawings.

10 In the application of mechanical refrigerating units to household refrigerators of the small size so commonly found in apartment houses it is particularly essential that the refrigerating unit occupy the minimum 15 space, be produced at the lowest possible cost, and operate with the minimum expense. My invention concerns itself with the production of a refrigerating unit designed to meet these requirements and in 20 the drawings accompanying this specification and forming a part thereof I have shown, for purposes of illustration, two forms which my invention may assume. In these drawings:

25 Figure 1 is a section through the ice chamber of a refrigerator showing one form of refrigerating unit embodying my invention,

30 Figure 2 is an end view of the unit shown in Figure 1 looking from the left,

Figure 3 is a view similar to Figure 1 but showing a second form of refrigerating unit also embodying my invention, while

35 Figure 4 is a view similar to Figure 2 but showing the form of unit illustrated in Figure 3.

40 In the drawings I have shown a refrigerator 11 provided with a refrigerating chamber 12 adapted to receive the refrigerating unit and communicating with the remainder of the refrigerator 11 by means of an outlet 13 positioned in the bottom wall of the refrigerating chamber 12 and an inlet positioned in one of the side walls of the 45 refrigerating chamber 12 and not shown herein.

45 The refrigerating unit illustrated in Figures 1 and 2 comprises an indirect expansion tank 14 filled with any suitable heat 50 conducting material such as brine, formed annular in shape to permit the insertion into the central opening thereof of a suitable ice pan 15 in which ice may be formed, and adapted to receive interiorly of itself a suit-

able helix 16 provided with an inlet 17 communicating through an expansion valve 18 with a duct 19 leading from a compressor (not shown) and provided further with an outlet 20 communicating through a direct expansion coil 21 and a thermostat unit 22 with a duct 23 leading back to the compressor. The expansion tank 14 is herein shown as supported from the refrigerator 11 by means of rods 24 extending across the ice chamber 12 and the expansion coil 21 as supported from the expansion tank 14 by means of a bracket 25 carried by the upper side of the tank 14.

55 The expansion coil 21 is also shown herein as extending from a point near that end 60 of the tank 14 at which the coil 21 is connected to the helix 16 to a point substantially removed from the other end of the tank 14 to thus reserve above the tank 14 a space adapted to receive the expansion valve 65 18 and thermostat unit 22 to permit the expansion valve 18 and thermostat unit 22 to be mounted within the general confines of the remainder of the unit and thus reduce 70 the space required for the unit. The space 75 required is still further reduced by the positioning of the ducts 19 and 23 leading to the compressor within the confines of the coil 21 and in addition the amount of space necessary for a given amount of cooling is 80 still further reduced by the use of a direct 85 acting coil 21 which is both cheaper and more efficient than a plurality of further indirect acting tanks 14 and the use of which therefore lowers both the initial cost and 90 operating expense of the unit.

95 The refrigerating unit illustrated in Figures 3 and 4 comprises a direct expansion tank 26 into which the refrigerant may directly expand, formed annular in shape to 100 permit the insertion into the central opening thereof of a suitable ice pan 15 in which ice may be formed, and provided with an inlet 27 in communication through an expansion valve 18 with a duct 19 leading 105 from a compressor (not shown) and provided further with an outlet 28 in communication through a direct expansion coil 21 and a thermostat unit 22 with a duct 23 leading back to the compressor. The expansion tank 26 is herein shown as supported from the refrigerator 11 by means of rods 110 24 extending across the ice chamber 12 and

the expansion coil 21 as supported from the expansion tank 26 by means of a bracket 25 carried by the upper side of the tank 26.

The expansion coil 21 is also shown here 5 in as extending from a point near that end of the tank 26 at which the coil 21 is connected to the outlet 28 of the tank 26 to a point substantially removed from the other end of the tank 26 to thus reserve above the 10 tank 26 a space adapted to receive the expansion valve 18 and thermostat unit 22 to permit the expansion valve 18 and thermostat unit 22 to be mounted within the general confines of the remainder of the unit 15 and thus reduce the space required for the unit. The space required is still further reduced by the positioning of the ducts 19 and 23 leading to the compressor within the confines of the coil 21 and in addition the 20 amount of space necessary for a given amount of cooling is still further reduced by the use instead of indirect acting tanks of not only a direct acting coil 21 but also a direct acting tank 26 which are both 25 cheaper and more efficient than the indirect acting tanks which they replace and the use of which therefore lowers both the initial cost and operating expense of the unit.

It will be apparent to those skilled in the art that I have provided two forms of refrigerating unit suitable for the purposes for which they were designed and accomplishing the objects of my invention. It will also be apparent to those skilled in the art that the particular structures herein shown may be used, either in whole or in part, in installations other than those for which they were particularly designed and that they may be variously modified without sacrificing the advantages or departing from the spirit of my invention. It will therefore be understood that the disclosure herein is illustrative only and that my invention is not limited thereto.

I claim:

In combination, an indirect expansion chamber, a direct expansion coil in communication therewith and disposed longitudinally above said indirect expansion chamber, and horizontally disposed means supported by said indirect expansion chamber arranged to support said direct expansion coil.

In testimony whereof, I hereunto affix my signature.

CHARLES C. SPREEN.
